UNITED STATES PATENT OFFICE.

JESSE VANCE MATTESON, JR., OF SANTA ROSA, CALIFORNIA.

ORTHO ROTOR PLANE.

Application filed November 24, 1926. Serial No. 150,617.

This invention relates to what I term an ortho-rotor plane; that is, a plane particularly adapted for the use of orthodontists in the shaping of the plaster casts used in the practice of dentistry. The object of the invention is to provide a simple, compact and easily portable power plane of a nature adapted to act upon these plaster casts, which may be operated from an ordinary electric light socket and which will render it possible for the dentist to do by power, work that has heretofore been accomplished by hand, at the expense of much time and labor.

Further objects and advantages of the invention will be set forth in the detailed description which follows.

In the accompanying drawings,

Fig. 1 is a view partly in side elevation and partly in section of the device of the present invention, showing the cover slightly separated from the casing.

Fig. 2 is a view of a closure section of the casing.

Fig. 3 is a side view of the apparatus in working position. It is at right angles to Fig. 1, but is still a side elevation because Fig. 1 shows the carrying position of the apparatus while Fig. 3 shows the working position of the apparatus wherein the casing is laid down on its side.

Fig. 4 is an end view of the closure section of the casing, and

Fig. 5 is a detail view of the cutting mechanism or plane assembly.

Like numerals designate corresponding parts in all of the figures of the drawings.

Referring to the drawing, 5 designates a casing provided with a carrying handle 6, and rubber knobs or other supporting feet 7. A partition 8 divides the casing into compartments 9 and 10. The compartment 9 receives a motor 11. The casing carries a plug-in socket 12 by which current may be supplied to the motor from any ordinary electric light connection in the office of a dentist or other user of the appliance. The circuit to the motor includes a controlling switch 12 of a usual and known construction. The shaft 13 of the motor carries a grooved pulley 14 over which a cable 15 passes. This cable passes over grooved idler guide pulleys 16 and 17 and over a correspondingly grooved pulley 18, which is fast upon the shaft 19 of a rotary planing blade 20. From this it is clear that rotation of the

motor will impart rotation at comparatively high speed to the blade of the rotary plane. The shaft of the rotor blade is journaled in bearings of an antifriction character indicated at 21 and 22 and is additionally supported upon a thrust bearing 23 by which the weight of the shaft and blade are carried. By referring to Fig. 2 it will be seen that the casing comprises a portion 5^a which is in the nature of an extension. That is, it projects beyond the line of the main portion of the casing so that when the casing is laid down upon its back, as in Fig. 3, this projecting portion of said casing will constitute what is, in effect, a projecting ledge. This projecting portion of the casing carries a track 26 upon which a sliding table 27 has movement, it being manifest that this movement is across the face of the rotary blade of the plane. The space beneath said sliding table is utilized to receive a plaster drawer 27^a. Compartment 10 is likewise utilized for the reception of a plaster drawer 28. A sliding glass pane 29 is mounted in guides 30 of the casing and, when the device is in use, may be drawn out into the path of the flying particles of plaster cut off by the plane blades, to constitute a baffle, to catch such flying particles and to prevent them from being thrown out into the room. A cover 30^a carries snap fastenings 31 adapted to engage with complementary members 32 upon the casing 5, said cover serving when in place, to close the casing 5 and to house the projecting portions of pulley 18, plane blade 20 and the sliding table.

Heretofore the shaping and trimming of the plaster models used by dentists in the practice of their profession, have been done by a knife and a small block plane, these instruments having been manually manipulated. The trimming of the plaster used can be fairly readily accomplished by hand if performed within twenty-four hours after the plaster has been poured. However, it is not always convenient to trim the cast within that time and if the plaster has set for a longer period of time than that, its hardness is such as to make the operation of shaping the same by hand both time consuming and arduous. In the use of the plane of the present invention, the degree of dryness makes no difference as far as the rapidity of the finishing is concerned and the angles and surfaces obtained are uniformly accurate. I am a practicing dentist

and my experience indicates that the average orthodontist can save, as a minimum, a hundred hours a year by the use of the machine of the present invention, with the additional advantage that the finished work will present more accurate angles and more smoothly finished surfaces than can be obtained by the old hand method.

It is to be understood that the invention is not limited to the precise construction set forth but that it includes within its purview whatever changes fairly come within either the terms or the spirit of the appended claims.

Having described my invention what I claim is:

1. A device of the character described comprising a casing, an assembly comprising an electric motor, a vertically disposed rotary plane blade and driving connections between the plane blade and the rotor, said assembly being disposed diagonally across said casing and a table slidable across said casing outside of said plane blade.

2. A device of the character described comprising a portable containing casing shaped to form a projecting ledge at one side, an electric motor within the casing, a vertically disposed plane blade at that side of the casing adjacent said ledge and at the juncture of the casing with said ledge, driving connections between the motor and the plane blade and a sliding table supported upon the ledge and movable across the face of the plane blade.

3. A structure as recited in claim 2 in combination with a cover adapted to rest upon said ledge and house the plane blade.

4. A structure as recited in claim 2 in combination with a slidable baffle adapted to be moved with respect to the main body of the casing and to a position where it will overlie the projecting ledge and act to catch particles of plaster dislodged by the plane blade.

5. A device of the character described comprising a casing having a body portion and a projecting portion which extends beyond said body portion, said casing being adapted to rest either upon its bottom or upon its side, a carrying handle upon the top of the casing, the projecting portion of the casing constituting a ledge when said casing is supported upon its side, trackways

carried by the projecting portion of the casing, a table slidable upon said trackways, an electric motor in the casing, a plane blade which is vertically disposed when the casing rests upon its bottom, driving connections between the motor and the plane blade and a baffle slidably mounted upon the main portion of the casing and movable to a position where it overlies the projecting portion of the casing, as and for the purposes set forth.

6. A device of the character described comprising an electric motor, the shaft of which carries a grooved pulley, a vertically disposed plane blade, means for mounting the shaft of said plane blade for rotation, a grooved pulley carried by the shaft of the plane blade, a pair of grooved idler pulleys, a cable passing over all of the grooved pulleys through which rotation of the electric motor is imparted to the rotary plane blade and slidable means for moving work across the face of the plane blade.

7. A device of the character described comprising a portable containing casing shaped to form a projecting ledge at one side, an electric motor within the casing, a vertically disposed plane blade at that side of the casing adjacent said ledge and at the juncture of the casing with said ledge and driving connections between the motor and the plane blade.

8. The combination with a portable supporting casing, of an electric motor disposed upon its side therein with its shaft substantially horizontally disposed, a rotary plane blade disposed therein with its axis vertically disposed, means for driving the plane blade from the motor and a work carrying table supported within and by the portable casing and mounted to slide across the face of the plane blade.

9. The combination with a supporting casing of an electric motor horizontally disposed therein and extending diagonally thereof, a rotary plane blade vertically disposed therein, a work table supported within and by the portable casing and mounted to slide across the face of the plane blade and a pulley and cable drive between the shaft of the motor and the plane blade.

In testimony whereof I affix my signature.

JESSE VANCE MATTESON, JR.
